[57] CLAIM

The ornamental design for a chair, as shown and described.

DESCRIPTION

FIG. 1 is a front perspective view of a first embodiment of a chair according to my new design;

FIG. 2 is a right side perspective view of the first embodiment;

FIG. 3 is a left side perspective view of the first embodiment;

FIG. 4 is a top perspective view of the first embodiment;

FIG. 5 is a bottom perspective view of the first embodiment;

FIG. 6 is a rear perspective view of the first embodiment;

FIG. 7 is a front perspective view of a second embodiment of a chair according to my new design;

FIG. 8 is a right side perspective view of the second embodiment;

FIG. 9 is a left side perspective view of the second embodiment;

FIG. 10 is a top perspective view of the second embodiment;

FIG. 11 is a bottom perspective view of the second embodiment; and,

FIG. 12 is a rear perspective view of the second embodiment.

The dashed lines in the drawings represent stitching. The rotational position of the seat on the column of the base and the rotational positions of the casters on the legs of the base vary among the figures. The adjustment levers are not visible in FIGS. 5 and 11, inasmuch as they are hidden by the legs of the base.
